DESIGN FOR A WRAP COVER FOR CANNED PRODUCTS

Moses Buchalter, New York, N. Y.

Application November 27, 1937, Serial No. 73,231

Term of patent 7 years

To all whom it may concern:

Be it known that I, Moses Buchalter, a citizen of the United States, and resident of the Bronx, New York, in the county of the Bronx and State of New York, have invented a new, original, and ornamental Design for a Wrap Cover for Canned Products, of which the following is a specification; reference being had to the accompanying drawing, forming a part thereof.

Fig. 1 is a front perspective view of a wrap cover for canned products, showing my new design.

Fig. 2 is a rear perspective view of the same.

Fig. 3 is a developed view of same.

I claim:

The ornamental design for a wrap cover for canned products, as shown.

MOSES BUCHALTER.
